TEXTILE FABRIC

Filed May 21, 1937

INVENTOR

A handwritten signature in black ink, appearing to read "J. W. B. Brooks". The signature is fluid and cursive, with a large, stylized "J" at the beginning. The name is written in a single, continuous line.

UNITED STATES PATENT OFFICE

104,958

DESIGN FOR A TEXTILE FABRIC

Jonathan W. B. Brooks, Philadelphia, Pa.

Application May 21, 1937, Serial No. 69,458

Term of patent 3½ years

To all whom it may concern:

Be it known that I, Jonathan W. B. Brooks, a citizen of the United States of America, residing in Philadelphia, county of Philadelphia, and State of Pennsylvania, have invented a new, original, and ornamental Design for a Textile Fabric, of which the following is a specification, reference being had to the accompanying drawing, forming part thereof, wherein,

The figure is a plan view of a piece of textile fabric showing my new design.

I claim:

The ornamental design for a textile fabric, substantially as shown.

J. W. B. BROOKS.
